FIREARM AND AMMUNITION THEREFOR

Gustav Tauschek, New York, N. Y.; vested in the
Alien Property CustodianApplication October 22, 1938, Serial No. 236,465
In Austria October 22, 1937

14 Claims. (Cl. 42—3)

My invention relates to a fire-arm of the kind in which projectiles are fired by gas-pressure from a barrel and has for its object a new kind of firing the arm by means of an electric ignition bridge. Other objects of the present invention will be evident as the description progresses.

One mode of carrying out the present invention is illustrated by way of example in the accompanying drawing.

Fig. 1 is a longitudinal section of a gun embodying my invention; Fig. 2 is a view of the gun in firing position; Fig. 3 is a cross section on line A—B of Fig. 1; Figs. 4 and 5 are longitudinal sections of two forms of my novel ammunition.

The barrel 1 is fitted into the electrically insulated part of a casing 2 and is fixed therein by a screw 3. The projectiles 4, which are successively inter-connected to form a projectile-train, are pushed through the casing 2 and into the barrel 1 to such extent, that the first projectile is disposed in the barrel 1. A fireproof insulating and packing ring 6 as well as a washer 7 and a guide-sleeve 8 are arranged between the barrel 1 and the casing 2, while the second projectile, which is secured by a pawl 5 pivoted to the casing 2, rests in the free space within the members 6, 7 and 8. The inside diameter of the sleeve 8 and of the rear end of the barrel is larger than corresponds to the outside diameter of the projectiles and the projectiles are adapted to rest on ribs 9, projecting into said sleeve and rear end of the barrel and thus give a good contact.

The pawl 5 controls a contact 10 in such a manner, that an electric current passes by way of the latter and the screw 3 to the barrel 1 in the engaged position of the pawl 5 only.

Further a tube 11 is secured to the barrel 1 and forces back a rod 12 during the discharge of the projectile from the barrel, whereby the projectile-train is fed forward the extent of a projectile by a feed-lever 13, pivoted to the end of the rod 12. The latter is subjected to the action of a spring 29 which, whenever the gas-pressure ceases in the barrel, pushes forward the rod 12 and thereby advances the projectile-train, so that the next projectile is fed into its firing position.

The projectile-train consists of a number of interconnected projectiles, which may be constructed for instance as shown in Fig. 4 or 5 and by means of grooves 14 and extensions 15 are united to form a flexible chain of projectiles. The projectiles are insulated from one another by means of paper or like insertions 16. In the construction illustrated in Fig. 4, the hollow chamber 17 of the projectile, which serves for the reception of the gun-powder charge, is lined with a cardboard sleeve 18 provided with an ignition bridging wire 19, which interconnects the two adjacent projectiles in the manner as illus-

trated. The cardboard sleeve 18 also prevents it, that the pointed end 20 of the projectile is forced into the chamber 17 of the projectile. For this object, in the construction illustrated in Fig. 5, the gun-powder chamber 17 is narrower and the bridging wire 19 is coiled and located in front of the projectile-end 20. A primer may be glued to the bridging wire in known manner. The projectiles are provided with a guide-collar 21, which engages the spiral grooves of the barrel, and therefore the projectiles may be made of a comparatively hard material (for instance soft steel), so that the force of percussion is increased very considerably.

15 The projectiles may be coated with a narrow strip of insulating varnish or the like 24 in order to prevent the flow of the current from the barrel 1 to the projectile resting in the sleeve 8, in case any carbon residues may have been deposited on the packing ring 6.

20 The fire-arm is operated in the following manner:

25 The projectile-train is pushed so far into the gun until the projectile is located in the barrel and now an electric contact 22 is closed, so that the electric current flows from a battery 23 by way of the contacts 22 and 10 to the barrel 1 and to the projectile located in the latter, and now the current passes by way of the ignition bridge to the next projectile and over the pawl 5 back to the battery. Thereby the gun-powder charge is ignited by the bridging wire 19 and thus the first projectile is fired. The projectile-train is fed forward by the action of the members 11, 12 and 13, and as soon as the pawl 5 engages the back of the following projectile, the ignition-contact and so forth are re-established until the contact 22 is opened again, so that firing ceases.

30 As shown Fig. 2, the projectile-train 4 may be wound up on a drum, which may carry the ignition battery 23, so that drum and battery may be replaced at the same time. A pocket battery is quite satisfactory for the ignition. However the gun may be connected to any convenient source of current.

45 I claim:

1. A fire-arm comprising a barrel, means for holding a plurality of projectiles and charges in tandem on the longitudinal axis of the barrel, means for holding one of said projectiles in a position in which it closes the barrel behind the projectile which is in the firing position, an electric ignition circuit connected with the barrel and adapted to be closed by two of the connected projectiles for firing the projectile which is in the firing position, and means for feeding the projectiles forwardly in the barrel to bring one projectile into the firing position and another projectile into the position in which the barrel is closed as successive shots are fired.

2. A fire-arm comprising a barrel, means for holding a plurality of connected projectiles in tandem on the longitudinal axis of the barrel, means for holding the second projectile in a position in which it closes the barrel behind the foremost projectile which is in the firing position, an electric ignition circuit connected with the barrel and adapted to be closed by the foremost and the second projectiles for firing the foremost projectile, and means for feeding the projectiles forwardly in the barrel to bring the foremost projectile into firing position and the next projectile into the position in which the barrel is closed as successive shots are fired.

3. Fire-arm ammunition comprising a plurality of chambered projectiles connected in tandem fashion, the connection being of such character as to enable the projectile located in front to detach itself from the projectile in the rear upon the firing of such front projectile, electrical igniting means located within each projectile, a propelling charge contained in the chamber of each projectile and connections permitting a current to travel from one projectile to the electrical igniting means of the next projectile ahead, to ignite the propelling charge therein.

4. In a plurality of projectiles in tandem fashion for fire-arms, means on each projectile for engaging the adjacent projectile to form a train of connected projectiles, an ignition wire in each projectile and electrically connecting the adjacent projectile, and means on each projectile adapted to be engaged by members of a fire-arm for holding one of said projectiles in the position in which it closes the barrel of the fire-arm and for feeding the projectiles forwardly in the barrel.

5. In a plurality of projectiles in tandem fashion for fire-arms, a compartment in each projectile containing an electric fuse and a propelling charge, means including an insulating means on each projectile for engaging the adjacent projectile to form a train of connected projectiles and means on each projectile adapted to be engaged by members of a fire-arm for holding one of said projectiles in the position in which it closes the barrel of the fire-arm and for feeding the projectiles forwardly in the barrel.

6. In a plurality of projectiles in tandem fashion for fire-arms, a compartment in each projectile, means carrying an electric fuse located in said compartment, a propelling charge in said compartment, means including an insulating means on each projectile for engaging the adjacent projectile to form a train of connected projectiles and means on each projectile adapted to be engaged by members of a fire-arm for holding one of said projectiles in the position in which it closes the barrel of the fire-arm and for feeding the projectiles forwardly in the barrel.

7. Fire-arm ammunition comprising a plurality of projectiles connected in tandem fashion, means for holding propelling charges and electrical igniting means between said projectiles and means for establishing electric contact between adjacent projectiles by means of the igniting means.

8. In a plurality of projectiles in tandem fashion for fire-arms, an electrically insulating coat covering part of each projectile, means including the insulating coat for connecting adjacent pro-

jectiles to form a train of mechanically connected but electrically insulated projectiles, and means on each projectile adapted to be engaged by members of the fire-arm for feeding the projectile forwardly in the barrel of the fire-arm.

9. A fire-arm comprising a barrel, adapted to receive two projectiles with propelling charges and electrical igniting means, means for holding the second of said projectiles in a position in which it closes the breech of the barrel behind the first projectile which is in firing position, and means for applying a difference of electrical potential between the projectiles for operating the electrical igniting means to fire the first of said projectiles through the barrel.

10. A fire-arm comprising a barrel, means for feeding a plurality of projectiles, charges and electrical igniting means in tandem forwardly in the barrel, an electric circuit connected with the barrel and adapted to be closed by the foremost projectile when the projectile comes into firing position for igniting the charge and firing the projectile and means for holding the second projectile in a position in which it closes the breech of the barrel while the foremost projectile is fired.

11. A fire-arm comprising a barrel, means for feeding a plurality of projectiles, charges and electrical igniting means in tandem forwardly in the barrel, an electric circuit connected with the barrel and adapted to be closed by the foremost projectile when the projectile comes into firing position for igniting the charge and firing the projectile, means for holding the second projectile in a position in which it closes the breech of the barrel while the foremost projectile is fired, and means operated automatically every time a shot is fired, for actuating the feeding means.

12. A fire-arm comprising a barrel, means for holding a plurality of projectiles, charges and electrical igniting means in tandem on the longitudinal axis of the barrel, means for transmitting current to said igniting means and means for effecting relative lengthwise movement of the projectiles to establish successively an operative relation between the said current transmitting means and the several electrical igniting means for successively firing projectiles through the barrel.

13. A fire-arm comprising a barrel, means for feeding a plurality of projectiles, charges and electrical igniting means in tandem forwardly in the barrel, an electric circuit connected with the barrel and adapted to be closed by the electrical igniting means of the foremost projectile when the projectile comes into firing position for igniting the charge and firing the projectile through the barrel, and means for controlling said circuit in step with the operation of said feeding means.

14. A fire-arm comprising a barrel, means for feeding a plurality of projectiles, charges and electrical igniting means in tandem forwardly in the barrel, an electric circuit connected with the barrel and adapted to be closed by the electrical igniting means of the foremost projectile when the projectile comes into firing position for igniting the charge and firing the projectile through the barrel, and manually operated means for controlling said circuit.

GUSTAV TAUSCHEK.
